Primary Examiner — Marie D. Fast Horse*(74) Attorney, Agent, or Firm* — Edell, Shapiro & Finn, LLC(57) **CLAIM**

The ornamental design for a removable display for a water purifier with docking station, as shown and described.

DESCRIPTION

FIG. 1 is a front, right, top perspective view of a removable display for a water purifier with docking station showing the new design.

FIG. 2 is a front, left, top perspective view thereof.

FIG. 3 is a rear, left, bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof; and,

FIG. 9 is a bottom plan view thereof.

The broken lines in the drawings depict portions of the removable display for a water purifier with docking station that form no part of the claimed design.
